MOISTURE RELEASE AND ALIGNING DEVICE

Patrick Dolan, Richmond, Va.

Application April 28, 1953, Serial No. 351,675

9 Claims. (Cl. 20—5)

This invention relates to building construction and more particularly to wall structures of composite characteristics where the outer surface covering is of the weatherboard or siding variety.

The type of structure to which reference is made is that wherein the outer surface covering comprises longitudinally disposed strips of weatherboarding or siding, generally produced from wood, so arranged that the upper edge portion of each strip is overlapped by the lower edge portion of the next adjacent strip. Under present prior art practices and in conformity with the various building codes, the composite wall structure contemplated is an exterior wall of a structure wherein the inner surface comprises plaster, plasterboard, wall board, or the like supported in the usual manner upon the inner faces of vertically disposed studs, the outer faces of said studs carrying the usual sheathing which, in turn, is covered by a layer of building paper, the weatherboarding to which reference has been made being secured to the studs by fastening elements which extend through building paper and sheathing.

The major failings and objectionable features of walls of this character arise out of the difficulties inherent to preventing paint from peeling and blistering from the weatherboarding, principally by reason of the accumulation of moisture between the weatherboarding and the building paper and sheathing. The principal source of such moisture stems from the drying out of the plaster, whether by interior building heat or otherwise, with the resultant movement of moisture present in an outward direction, through the sheathing and building paper, to accumulate upon the inner surfaces of the weatherboarding, from which point there is no escape.

The formation and accumulation of such moisture results not only in damage to the paint applied exteriorly to the weatherboarding but also results in the warping of the boarding whereby undesirable pockets or spaces are created, hastening the deterioration of the weatherboarding and injuriously affecting the appearance of the structure. Such conditions exist even where highly seasoned lumber is utilized for the weatherboarding, it being borne in mind that under modern requirements for housing facilities, the securing of properly seasoned lumber is virtually a commercial impossibility.

A further objectionable feature in connection with wall structures of the character presently under consideration arises out of the care required, and associated cost of construction, in ascertaining that the successive strips of weatherboarding are erected in precise parallelism whereby the perfection of appearance of the finished wall is not impaired.

With these prior art problems in mind, it is a major object of the present invention to provide a moisture release device whereby the possibility of accumulation of moisture behind strips of weatherboarding will be effectively prevented.

It is a further object of the invention to provide a moisture release device for use in connection with wall structure of the character set forth which can be readily installed simultaneously with the erection of the wall and which will be substantially invisible when the exterior surface of the wall is viewed.

2

It is a further objection of the present invention to provide a moisture release device for use in connection with wall structure of the character set forth which will not affect construction costs materially, construction methods, or wall appearance.

It is a still further object of the invention to provide a moisture release device which will automatically insure the proper and uniform securing of the weatherboarding to the wall studding.

It is a further object of the invention to provide a novel moisture release device for use in connection with wall structure of the class set forth which will automatically insure the proper alignment of each successive strip of weatherboarding, both as to parallelism and as to precise degree of overlap, with respect to the adjacent lower strip.

It is a further object of the present invention to provide a novel moisture release device for use in connection with wall structure of the character under contemplation which will be strong and durable, which may be manufactured with particular economy from readily available materials, which will be extremely simple to install, and which will require neither special tools for the installation thereof nor experience in the use thereof whereby relatively unskilled labor will be capable of producing finished wall structure of superior appearance.

Further objects and advantages of the invention will be readily apparent from the following description taken in conjunction with the accompanying drawing wherein:

Fig. 1 is a perspective view of a moisture release device constructed in accordance with the present invention;

Figure 2, a fragmentary perspective view, parts being illustrated in section, of a portion of an exterior wall constructed in accordance with the present invention;

Figure 3, a fragmentary perspective view, on an enlarged scale, illustrating a portion of the moisture release device;

Figure 4, a side elevation of a portion of the wall structure illustrated in Figure 2, parts being broken away for greater clarity;

Figure 5, a horizontal sectional view taken on the line 5—5 of Figure 4, looking in the direction of the arrows; and

Figure 6, a fragmentary detail elevation of a slightly modified form of moisture release device.

As shown in the drawings, particular reference being had to Figures 2, 3 and 4 thereof, a portion of an exterior wall constructed in conventional fashion has been illustrated, said wall including an inner facing or surface 10 of plaster, or the like, secured in the usual manner to spaced vertically disposed studs 11. In accordance with accepted building standards and code requirements, these studs are usually constructed of 2 x 4's and are spaced apart 16" from stud center to stud center. The exterior surfaces of these studs carry the usual sheathing 12 which, in turn, is covered by building paper 13, all as is well known in this art. The siding or weatherboarding 14 is positioned against the outer surface of the building paper and maintained in position by suitable fastening elements 15 which extend through weatherboarding, building paper and sheathing, and are securely anchored in the studs 11.

Preferably the strips of weatherboard are of tapered construction, of greater thickness at the bottom than at the top and each strip includes an outwardly inclined face 16, a top edge 17, a bottom edge 18, and an inner inclined face 19, the upper portion 20 of the inner face being substantially vertically disposed and this portion only on each strip 14 contacting the adjacent surface of the building paper 13. A portion of the lower edge of each strip of weatherboarding 14 overlaps a portion of the upper edge of the adjacent strip and thus air spaces 21 are pro-

vided between the outwardly inclined inner weatherboarding surfaces 19 and the building paper 13.

With the above described structure in mind, the present invention contemplates the provision of novel spacing means for disposition between the overlapped portions of adjacent strips of weatherboarding to accomplish the ready release of such moisture as may accumulate in the air spaces 21 behind the strips of weatherboarding.

One embodiment of such moisture release means has been disclosed in Figure 1 of the drawings and comprises a strip 22 of material having uniformly spaced offset portions. Desirably, wire or stock of suitable gauge may be employed for the production of such strip material, however, any other suitable material of appropriate thickness may be employed with equal facility. As illustrated, the strip material includes straight stretches or lengths 23 separated by uniformly spaced offset portions 24 lying in the same plane as the lengths 23 and united at the outer extremities thereof by angularly disposed loop-like spacing portions 25 which extend at substantially right-angles to said offset portions a distance substantially equal to the degree of overlap of weatherboarding desired. The spacing of the loop-like portions 25 is critical and it is contemplated that the distance between the centers of adjacent loops will be fifty percentum of the distance between adjacent studs, thus the distance between the centers of alternate loops should be precisely that of the distance between the centers of adjacent studs, for a reason to be described more fully hereinafter.

These moisture release strips or devices 22 may be produced from continuous stock or prefabricated in given lengths. Desirably, an eight foot length has been found to be particularly convenient, it being understood that the nature of the material is such that the severance of a portion thereof, where multiples of preformed lengths are in excess of the extent of the wall structure being erected, presents no problem.

The installation and use of the moisture release strips thus described is particularly simple and is accomplished simultaneously with the construction of the wall in the following preferred manner. After the lowermost strip of weatherboarding has been properly aligned and secured to the studding by appropriate fastening elements, a moisture release strip 22, or the required number of such strips, is positioned upon the upper edge 17 of the secured weatherboarding with the straight stretches 23 resting upon such upper edge and with the depending loop-like portions 25 in face-to-face contacting relationship with the upper portion of the inclined outer face 16 of the strip of weatherboarding. Proper positioning of the moisture release strips 22 provides a loop-like portion 25 in alignment with the center line of each stud 11 and the width of the offset portions 23 is less than that of the top edge of the weatherboarding so that the loop-like portions 25 will not be spaced outwardly from the inclined face 16 of the weatherboarding. Since no stress is placed upon the moisture release strip or strips 22, these elements will remain in place, however, in the event that it is desired to guard against inadvertent displacement thereof prior to the positioning and securing of the next higher strip of weatherboarding, certain of the loop-like portions 25 may carry sharpened tack-like projections 26 on the inner faces thereof, intended to be pressed into the adjacent weatherboarding surfaces as will be apparent from an examination of Figure 2 of the drawing. In practice, where such tack-like projections are employed, it has been found that three such projections or elements are adequate for an eight foot length of moisture release striping. Alternately, these tack-like elements may be carried below the straight stretches 23 of the moisture release strip, as indicated at 27 in the modified embodiment of the invention illustrated in Figure 6 of the drawings, or, as stated hereabove, such elements may be dispensed with altogether, or a greater or lesser number may be provided.

With the moisture release striping thus installed, the

next adjacent strip of weatherboarding is positioned in overlapping relationship with respect to the secured strip and associated moisture release device. Positioning the lower edge 18 of said overlapping strip of weatherboarding in alignment with the lowermost portions of the loop-like portions 25 will insure an accurate degree of overlap and a correct alignment of this overlapping strip which is then secured in position by fastening elements or nails driven into the studding through the loop-like portions 25 of the moisture release device, as clearly illustrated in Figure 4 of the drawings. It will be understood that each nail passes through the overlapped portions of adjacent strips of weatherboard, through the associated loop-like portion 25 and into a stud 11.

With the wall construction thus described, moisture release spaces 28 will be provided between the overlapped portions of adjacent strips of weatherboarding, reference being had to the inner face 19 of the outermost or upper strip of boarding and the outer inclined face 16 of the undermost strip of weatherboarding. These moisture release spaces have been illustrated in Figure 5 of the drawings and extend between adjacent loop-like portions 25, it being understood that the widths of such loop-like portions is not sufficient to interfere with proper release and/or evaporation of moisture, and furnish communication between the atmosphere and the air spaces 21 provided between the inner faces of the strips of weatherboarding and the outer surface of the building paper 13.

It is to be noted that in actual practice the air spaces 21 are affected to some degree by the fact that the building paper therebeneath tends to open or expand outwardly to some slight degree from the adjacent sheathing, under outward pressure from moisture passing therethrough from the inner or plastered surface of the wall. Where these spaces 21 are in communication with the atmosphere, as by the provision of the spaces or outlets 28, possibility of warping or other deterioration of the weatherboarding has been effectively prevented.

It will be understood that each succeeding strip of weatherboarding is installed in a manner identical to that described hereabove and, without any requirement for especially skilled labor, careful measurement or other laborious precautions, properly aligned wall structure may be erected with a positive assurance that each successive strip of weatherboarding will be uniformly overlapped, in precise parallelism, and with the fastening elements entering into the supporting studding and in vertical alignment.

While the moisture release strips have been illustrated and described as fabricated from wire stock of substantially circular cross-sectional configuration, it will be understood that flat strip material may be employed with equal convenience, having solid rather than loop-like spacing elements or portions, it only being necessary that the strip material be of an appropriate thickness and of such character as to be readily penetrable by the fastening elements 15 or, if desired, apertures may be provided in the depending offset portions for the passage of such fasteners.

Moisture release means for an overlapped weatherboard or siding wall structure has thus been provided which can be produced with particular economy and which will effectively prevent any possibility of the accumulation of moisture behind the strips of boarding. With this structure there will be no peeling or blistering of exterior paint resultant from moisture accumulation. Further, deterioration of the strips of weatherboarding from this and related causes will be prevented. The structure is such that no skilled labor is required for the installation of the novel moisture release means and, simultaneously therewith, assurance is provided that successive strips of boarding will be accurately aligned and properly secured in position.

It will be understood that in the building trades and in other related industries there are various and obvious

additional uses for the present invention. Examples thereof are in connection with the construction of roofings where shingles or the like are employed or in the manufacture of ventilated containers where overlapped wall structure is desired. Accordingly, the invention is not considered restricted by that which is shown in the drawings and described in the specification but only as illustrated in the appended claims.

What is claimed is:

1. In a wall construction having a plurality of elongated rows of strips of weatherboarding disposed horizontally in overlapping relationship to provide an air pocket behind each row, each of said strips being thicker at the bottom than at the top and having top and bottom edges, moisture release and aligning means comprising an elongated strip of material having aligned straight stretches separated by horizontally disposed offset portions lying in the same horizontal plane as said straight stretches and a spacing portion depending downwardly from the extremity of each of said offset portions, the straight stretches resting upon the upper edge of a strip of weatherboarding and the downwardly depending spacing portions being positioned between the front face of said strip of weatherboarding and the overlapping portion of the next higher strip of weatherboarding to provide elongated spaces between the overlapped portions of said strips of weatherboarding furnishing communication between the atmosphere and the air pocket behind said next higher strip of weatherboarding, the bottom edge of said next higher strip of weatherboarding being located in alignment with the extremities of said spacing portions to align said strip of weatherboarding horizontally and control the degree of overlap.

2. Moisture release and aligning means of the class set forth comprising a strip of wire like material including straight aligned stretches separated by pairs of offset portions disposed in substantial parallelism and lying in the same plane as said straight stretches, the extremities of each pair of offset portions being united by a loop-like portion angularly disposed with respect to said offset portions, all of said offset portions extending in the same direction from said aligned straight stretches.

3. Moisture release and aligning means as set forth in claim 2 having relatively sharp fastening means carried by certain of said loop-like portions.

4. Moisture release and aligning means as set forth in claim 2 having relatively sharp fastening means carried by certain of said straight stretches.

5. In a wall construction having a plurality of elongated rows of strips of weatherboarding disposed horizontally in overlapping relationship to provide an air pocket behind each row, each of said strips being thicker at the bottom than at the top and having top and bottom edges and inclined front and rear faces, moisture release and aligning means comprising an elongated strip of wire-like material positioned upon the top edge of each strip of weatherboarding, said moisture release means including a plurality of aligned straight stretches separated by a pair of forwardly projecting offset portions disposed in substantial parallelism and lying in the same horizontal plane as said straight stretches, the free extremities of each pair of offset portions being united by a downwardly depending loop-like spacing portion, said spacing portions being positioned between the front face of the strip of weatherboarding upon which said moisture release means is positioned and the rear face of the overlapped portion of the next higher strip of weatherboarding to provide elongated spaces between the overlapped portions of said strips of weatherboarding furnishing communication between the atmosphere and the air pocket behind said next higher strip of weatherboarding to release moisture accumulated in said air pocket, the bottom edge of said next higher strip of weatherboarding being located in alignment with the free extremities of said spacing portions to align said strip of weatherboarding and control the degree of overlap.

6. The structure set forth in claim 5, said moisture release and aligning means having relatively sharp tack-like fastening means carried by certain of said loop-like spacing portions and adapted for engagement with the front face of the strip of weatherboarding upon which said moisture release is supported.

7. The structure set forth in claim 5, said moisture release and aligning means having relatively sharp tack-like fastening means carried by certain of said straight stretches and adapted for engagement with the top edge of the strip of weatherboarding upon which said moisture release means is supported.

8. In a wall construction including a plurality of uniformly spaced vertically disposed studs having a plurality of elongated rows of strips of weatherboarding secured thereto, said weatherboarding being disposed horizontally and in overlapping relationship to provide an air pocket behind each row, each of said strips being thicker at the bottom than at the top and having substantially horizontally disposed top and bottom edges and inclined front and rear faces, moisture release and aligning means comprising an elongated strip of wire-like material positioned upon the top edge of each strip of weatherboarding, said moisture release means including a plurality of aligned straight stretches separated by a pair of forwardly projecting offset portions disposed in substantial parallelism and lying in the same horizontal plane as said straight stretches, the extremities of each pair of offset portions being united by a downwardly depending loop-like spacing portion, said spacing portions being positioned between the front face of the strip of weatherboarding upon which said moisture release means is positioned and the rear face of the overlapped portion of the next higher strip of weatherboarding to provide elongated spaces between the overlapped portions of said strips of weatherboarding furnishing communication between the atmosphere and the air pocket between said next higher strip of weatherboarding to release moisture accumulated in said air pocket, the bottom edge of said next higher strip of weatherboarding being located in alignment with the lowermost extremities of said loop-like spacing portions to align said strip of weatherboarding and control the degree of overlap, the distance between adjacent loop-like spacing portions being equal to half the distance between adjacent studs so that said moisture release means is positioned upon the top edge of a strip of weatherboarding with alternate loop-like spacing portions in alignment with adjacent studs whereby fastening means driven through the overlapped portions of said strips of weatherboarding within the confines of said alternate loop-like spacing portions will enter into said studs.

9. A device for facilitating the alignment of overlapped siding units in wall construction and for providing a space for the release of moisture therebetween, said device comprising a length of material lying in a single plane, spaced laterally offset portions lying in the same plane and extending to one side of said strip, and angularly disposed spacing portions of a thickness at least corresponding to the spacing desired extending downwardly in a single plane from said offset portions for accommodating fastening elements extending through the overlapped portions of said units, said spacing portions being concealed between the overlapped portions when the device is in use.
